COMPENSATING DEVICE FOR MOTOR VEHICLES

Hugo Höme, Essen, Germany

Application December 17, 1934, Serial No. 757,980
In Germany December 18, 1933

6 Claims. (Cl. 267—11)

Compensating devices for motor vehicles are known, in which relative movements between the axles and the underframe occurring on one side of the car are transmitted mechanically by rods 5 upon the part of the underframe situated on the other side of the car, so that the underframe is shifted parallel to itself. These devices have not stood the test in practice as they transmit also all rapid oscillations and are thereby destroyed in 10 a very short time. Hydraulic compensating devices have then been employed, in which conduits lead from one side of the car to the other side of the same. It is, however, scarcely possible to maintain tight the pipe connections of the conduits owing to the high pressures which occur.

The inconveniences of the devices of known construction are avoided by the invention in a simple manner in that the hydraulic compensator is preserved, and the transmission of the movements from one side of the car to the other is effected mechanically by means of rods.

An embodiment of the invention is illustrated by way of example in the accompanying drawing in which:—

Fig. 1 shows a part of the device in side elevation.

Fig. 2 is a vertical section through this part of the device on enlarged scale.

Fig. 3 shows in perspective view the device 30 mounted on one side of the vehicle.

Fig. 4 is a longitudinal section of Fig. 3 showing the device in elevation.

In a similar manner as in the compensating devices of known type a casing 1 is rigidly connected with the underframe of the car on each side of the same. This casing 1 is tightly closed by a cover 2 and by a bottom plate 3a. Each casing 1 comprises two cylinders 3 and 4. In each cylinder two pistons 5, 6 and 7, 8 respectively are shiftable arranged. The upper pistons 5 and 7 of the casings are hingedly connected by means of a strap 9, 9 respectively with a two-armed lever 10, the shaft 11 of which is tightly packed in the side walls of casing 1. On the end of shaft 11 projecting from the casing 1 a lever 12 is hingedly mounted with which a lever 13 is hingedly connected which is mounted on the car axle. Each piston 5, 7 has an axial bore 14, 15 respectively extending through the piston. A valve 17, 18 respectively, controlled by a feeble spring 16, is inserted in the corresponding bore 14, 15 so that, in the inoperative position shown in Fig. 2, it does not completely close the bore 14, 15 respectively. Piston rods 19, 20 of the pistons 6, 8 respectively extend through the bottom plates

of the corresponding cylinder 4 or 3 and have each a head 21, 22 respectively bearing on the corresponding face of a two-armed lever 23. Valves 26, 27 inserted in wide bores 24, 25 of the bottom of the corresponding cylinder 4, 5 are maintained in closing position by strong springs 26a, 27a respectively when the device is in the inoperative position. Valves 30, 31 controlled by feeble springs (not shown in the drawing) are mounted in second bores 28, 29 of the bottom plates of 10 cylinders 4, 5 and, similar to the valves 17, 18 do not completely close the bores 28, 29 when the device is in inoperative position. A cross-shaft 32 of the two-armed lever 23 is tightly packed in the walls of casing 1 and forms also the shaft 15 of the two-armed lever 23 of the compensating device situated on the other side of the car. On this cross-shaft 32 a lever 33 is mounted which is maintained by a spring 34 in a position corresponding to the inoperative position of the 20 whole device. The casing 1 and therefore the space between the pistons 5, 6 and 7, 8 and between the pistons 6, 8 and the bottom plates of the cylinder are filled with a not easily freezing liquid, for instance oil.

When the car is stopped and when it runs quietly, the elements of the device are in the position shown in Figs. 1 and 2. The oscillations of the car which occur also in this condition of the car and which take place very rapidly and 30 possess only a very small amplitude, do not influence the pistons 6 and 8 as, when the pistons 5 and 7 move only very little, the liquid can pass through the bores 14, 15 without closing the valves 17 and 18. The eddies occurring in this 35 instance damp the oscillations. If, however, a shock is acted upon the car so that for instance the lever 12 connected with the car axle oscillates in the plane of Fig. 2 in clockwise direction, the two-armed lever 10 causes descending of piston 40 1 so that the valve 18 is instantaneously closed. The liquid in the space between the pistons 7 and 8 is completely shut off so that it pushes downwards the piston 8. Herefrom results that valve 31 is closed and the liquid can flow out into the 45 hollow space of casing 1 only after the considerable resistance offered by the valve 27 has been overcome. The strength of the springs 26a, 27a is so calculated that the effect of the masses caused by the shock is already consumed. During this proceeding the piston rod 20 oscillates the two-armed lever 23 and through the intermediary of the cross-shaft 32 the corresponding two-armed lever 23 on the other side of the car 50 so that this second two-armed lever lifts the 55

piston corresponding to the piston 6, which in turn lifts its counterpart, whereby the lever on the other side of the car corresponding to lever 12 is also oscillated in clockwise direction so that 5 the other car side is moved by the same amount as the first car side. During the ascending of the pistons 6 and 8 the liquid flows in through the bores 28, 29, and losses of liquid in the spaces between the pistons 5, 6 and 7, 8 are compensated 10 by the oil flowing in through the bores 14, 15. The spring 34 permanently holds the two-armed lever 23 in the median position if the device is not operated.

This device does not require any pipe connections, and the pressure of the liquid on the casing 15 is never influenced so that no special packings are required for the shafts 41 and 32 extending through the casing wall.

I claim:—

- 20 1. A compensating device for vehicles, especially motor cars, comprising on the left hand and right hand of the car a similar casing filled with oil mechanically connected with one and the same axle of the car, each casing comprising two 25 cylinders, two pistons in each cylinder, the upper piston having an axial bore extending from the top to the bottom of the piston, a valve in the lower end of this bore, a shaft in the top portion of said casing, one end of said shaft extending from the casing, a two-armed lever on this shaft, links one at the end of each arm of said two- 30 armed lever connected with the corresponding upper piston, a cross-shaft in the lower portion of said casing below said cylinders and extending from said casing to the casing of the device on the opposite side of the car, a two-armed lever on this cross-shaft located in said casing, a piston rod downwardly extending from each of said 35 lower pistons and resting upon the correspond-

ing arm of said lower two-armed lever, and a discharge valve and a re-filling valve in the bottom piece of each cylinder.

2. A compensating device as specified in claim 1, comprising in combination with each casing and the shaft at the upper end of each casing, a lever hingedly mounted on the outer end of said shaft, and a lever hingedly connected with the outer end of said first mentioned lever and with an axle of the car. 5

3. A compensating device as specified in claim 1, comprising in combination with each casing and with the two cylinders in each casing, a discharge bore in the bottom wall of each cylinder, a valve in each discharge bore, and a strong 10 spring on the stem of each valve, said valves adapted to act as shock dampers. 15

4. A compensating device as specified in claim 1, comprising in combination with the casing, the two cylinders in said casing and the upper piston 20 in each cylinder, said piston having a central bore, a spring controlled valve in the lower end of each axial bore, a spring on the stem of said valve of such strength that the valve is not completely closed when the device is in inoperative 25 position.

5. A compensating device as specified in claim 1, comprising in combination with the casing and the two cylinders in said casing, each cylinder having an inlet bore on its bottom, a re-filling 30 valve in said bore.

6. A compensating device as specified in claim 1, comprising in combination with the lower cross-shaft extending from one casing to the other, a downwardly extending lever on the middle of said cross-shaft, and a spiral spring adapted to maintain said lever in the vertical 35 position.

HUGO HÖME.
